INVENTOR,
George Posnick.
BY
Harry W. Brown.
ATTORNEY.

UNITED STATES PATENT OFFICE.

GEORGE POSNICK, OF SPRINGFIELD, MASSACHUSETTS.

SHAVING-GAGE.

1,391,274.

Specification of Letters Patent. Patented Sept. 20, 1921.

Application filed December 20, 1920. Serial No. 431,901.

To all whom it may concern:

Be it known that I, GEORGE POSNICK, a citizen of the United States of America, residing at Springfield, in the county of Hampden and Commonwealth of Massachusetts, have invented certain new and useful Improvements in Shaving-Gages, of which the following is a specification.

This invention relates to improvements in gage devices for accurately determining the cutting line on which the hair at the forward and upper edge of the ear may be trimmed. It is particularly designed for persons who are in the habit of shaving themselves; as oftentimes it is difficult to accurately trim the hair at the same line on opposite sides of the head.

Broadly, the invention comprises a band of flexible material which is adapted to be temporarily placed on the head and located or placed above and around the rear part of the ear at one end of the band; the other end of the band being provided with a gage device which is placed against the opposite side of the head at the desired cutting line and in relation to the forward upper edge of the ear.

The invention is designed to be used with a safety or common razor, and in no way interferes with the usual use of the same.

Referring to the drawings: Figure 1 shows one form of the device as applied to the head and indicating that end to which the gage portion is attached.

Fig. 2 represents the opposite side of the head, showing the part that is attached to the ear.

Fig. 3 shows a slight modification which is designed to be attached to the ear and having a portion extending to the eye for the purpose of locating the cutting line with reference to the ear on one side of the head.

Fig. 4 is a perspective view of the form shown in Figs. 1 and 2, when detached from the head.

Fig. 5 is a perspective view of the form shown in Fig. 3 removed from the head.

Fig. 6 is a detail view of the part which engages the ear.

Referring to the drawings in detail: 1 and 2 designate strips of elastic material, as steel, similar to clock spring material, that are connected together in sliding relation by means of the bands 3 and 4. On one of the strips, as 2, is placed a scale indicated at 5 for the purpose of determining the relative

adjustment of the strips, whereby after the strips are once adjusted it will not be necessary for the user to again readjust the device. Attached to the end of the strip 1 60 is an arc shaped piece 6, preferably of wire, that freely slides through the loop 7. 8 is the gage member which is pivotally attached to the strip 2 by means of the pivot 9 which serves to connect the folded piece 10 65 which is bent so as to engage both of the inner and outer ends of the strip 2 and form the loop 11, and through which loop passes the wire 12 of the gage portion 8. The piece 10 is formed with a pointer part 13 which 70 moves over a scale 14 for the purpose of angularly adjusting the gage 8 with reference to the band 2, for the purpose of determining the angle at which the hair will 75 be trimmed. The gage portion proper, comprises oppositely extending arms 15, 16, 17, and 18, and the inwardly extending portions 19 and 20. The portions 15 and 20, and 17 and 19, rest against the side of the face indicated by the line 20'. The portions 18 80 and 19, and 16 and 20, serve as guides for the back edge 21 of the razor, indicated at 22. The portion 12, it will be noticed, is an integral part of the other members of 85 the gage, and passes through the loop 11 of the piece 10.

This device is used as follows: It is placed on the head, as indicated in Figs. 1 and 2, by placing the loop 6 so as to engage the upper rear edge part of the ear, as shown in Fig. 2. 90 The strips 1 and 2 are then adjusted to bring the gage 8 at the desired line with reference to the forward part of the ear where the trimming is to be made, whereby when the blade 22 of the razor is placed against the outwardly extending portions 16 and 18, the line on which the hair is to be trimmed, or the shaving commences will be accurately determined, and also the desired angle is determined, by means of the scale 14. After one 100 side of the head is trimmed, the device is removed and placed in reverse position on the other side of the head, when the same operation is carried out on that side.

In the modification shown in Fig. 3, instead of the ear piece 6 shown in Fig. 4 being used, the loop construction shown in Fig. 6 may be used, which comprises the portions 23 and 24 which engage the rear part of the ear. A loop 25 is provided for the 110 purpose of permitting the piece to be bent to fit the ear by adjusting the distance between

the upper and lower portions 23 and 24. It is understood that this ear piece is used in the same way as indicated in Fig. 2.

In the construction shown in Fig. 5 the pieces 1 and 2 which pass over the head are omitted and attached to the ear piece 26 is a strip of flexible material 27. The razor guide 8 is attached to the portion 28 of the ear piece 26 by means of the extensible strips 29, and the pivotal rivet 30, whereby the guide 8 may be turned and adjusted on the pivot to any desired angle. The strip 29 is made adjustable as to its length by any suitable structure, as the part 29 engaging the loop 31. The guide strip 27 is designed to be placed at a definite point adjacent the eye, as for example, 32.

It is to be understood that the ear piece 26, shown in Fig. 6, may be used with both forms of the device, as desired. In other words, the pieces 6 and 26 are interchangeable.

What I claim is:

1. In a device of the kind described, a member engaging the head, an ear engaging piece attached to said member, a razor blade guide device attached to said member, said guide device having projections to engage the side of the face and other projections to receive the rear edge of the razor, means for adjusting the angle of the guide device with relation to the head piece.

2. A device of the kind described, comprising a member adapted to engage the head, a member attached to the head member and

engaging the ear, the opposite end of the head engaging piece having a razor receiving guide connected thereto, means for adjusting said guide at any desired angle.

3. In a device of the kind described, the combination, a portion designed to be placed on the head of the wearer, a loop piece attached to said device and engaging the ear of the wearer, a guide device pivotally connected to the head engaging member and comprising oppositely projecting portions to engage the face of the user and receive the rear edge of a razor, whereby the blade of the razor may be positioned, as described.

4. In a guide device for use in determining the line at which the hair is to be trimmed at the forward and upper edge of the ears, and comprising a band adapted to be passed over the head of the user, one end of the band having a loop for engaging the upper and rear sides of the ear, the other end of the band having a razor receiving gage device pivotally connected thereto, said gage device having a plurality of projections that are arranged at an angle to each other for receiving the rear edge of a razor blade, as described.

5. A guide device for the purpose described, comprising a member adapted to be attached to the ear, a member connected thereto and designed to engage the head of the wearer for the purpose of positioning the said device, and a razor receiving guide device connected thereto.

GEORGE POSNICK.
